(57) **CLAIM**

The ornamental design for an organizer with receptacles, as shown and described.

DESCRIPTION

FIG. 1 is a front, perspective view of an organizer with receptacles showing a new design;

FIG. 2 is another perspective view thereof;

FIG. 3 is a front elevational view thereof;

FIG. 4 is a rear elevational view thereof;

FIG. 5 is a left-side elevational view thereof; the right side elevational view being an identical mirror image thereof;

FIG. 6 is a top plan view thereof; and,

FIG. 7 is a bottom plan view thereof.

(Continued)

The broken lines illustrate environment and form no part of the claimed design.

1 Claim, 6 Drawing Sheets
